MOLD FOR SOLE PRESSING MACHINES

Original Filed Aug. 15, 1928

UNITED STATES PATENT OFFICE

EDWARD J. GOODWIN, OF HAVERHILL, MASSACHUSETTS, ASSIGNOR OF ONE-HALF
TO JOSEPH O. PARIS, OF HAVERHILL, MASSACHUSETTS

MOLD FOR SOLE PRESSING MACHINES

Application filed August 15, 1928. Serial No. 299,844. Renewed January 31, 1930.

This invention relates particularly to a sole-leveling machine which includes an inner mold or form on which a partially completed shoe, without a heel, is supported, and 5 an outer mold having a molding face adapted to cooperate with the inner mold in leveling the outsole of the shoe, means being provided for moving one of said molds, relative to the other to compress the outsole, mold its outer 10 face, and press down the usual channel flap of the outsole.

The invention is embodied in a supplemental mold member adapted to bear on the heel end of the outer mold and cooperate 15 therewith and with the inner mold in compressing and molding the heel end of the outsole, in such manner as to form thereon a convex heel seat conforming to the recessed end of a wood heel, and a transverse shoulder 20 defining the forward end of the heel seat and offset therefrom, to overlap the upper portion of the heel breast, so that the sole-leveling operation provides the outsole with a heel seat adapted to closely fit the recessed 25 end of the heel and form a close joint at the upper portion of the breast thereof.

Of the accompanying drawings forming a part of this specification,—

Figure 1 is a side view, showing the outer 30 and inner molds of a sole-leveling machine in pressing relation with each other, and a supplemental mold member embodying the invention, a portion of a heelless shoe supported by the inner mold being shown by 35 dotted lines.

Figure 2 is a perspective view, and

Figure 3 an end view of the supplemental mold member.

Figure 4 is a section on line 4—4 of Figure 40 3.

Figure 5 is a section on line 5—5 of Figure 1.

Figure 6 is a section on line 6—6 of Figure 5.

Figure 7 is a fragmentary sectional view, 45 showing the heel end of the inner mold, the heel end of the outsole with its heel seat completed, and a portion of a wood heel of the Cuban type seated on the heel seat and ready 50 to be nailed thereto.

Figure 8 is a fragmentary perspective view, showing the heel ends of the upper and outsole, the latter being skived at its inner side preparatory to being molded to form the heel seat shown by Figures 7 and 10.

Figure 9 is a section on line 9—9 of Figure 8.

Figure 10 is a fragmentary perspective view, showing the heel ends of the upper and outsole, the heel seat being completed, a wood heel being shown by dotted lines seated on the heel seat.

Figure 10^a is a fragmentary side view, 65 showing a portion of the upper, a portion of the outsole with a completed heel seat, and a portion of the heel seated on the heel seat with a portion of its breast overlapped by the shoulder at the forward end of the heel seat.

The same reference characters indicate the 70 same parts in all of the figures.

In the drawings, 12 designates the inner mold or form of a well known type of sole-leveling machine, adapted to support a partly completed shoe without a heel, the heel end 75 of the outsole being designated by 13, the upper by 14, and the shank piece by 15. In preparing the outsole I skive the inner side of the heel end thereof, to provide it with a feather edge 16 (Figures 8, 9, and 10) which 80 is spaced from the shank piece before the pressing operation, as shown by Figures 8 and 9.

17 designates the outer mold which has the usual recessed molding face 18 indicated by 85 Figure 5, and by the dotted line in Figure 1, and adapted to exert leveling pressure on the outsole, as usual in sole leveling machines. The molds 12 and 17 may be elements of the well known Goodyear direct leveling machine, the inner mold 12 being horizontally movable and vertically immovable, while the outer mold 17 is horizontally immovable and vertically movable so that a shoe 90 may be applied to the inner mold while the latter is out of the path of the outer mold, and then be moved into said path preparatory to the leveling operation.

The supplemental mold member characterizing my invention includes a plate 19, 100

formed to extend across the heel end of the face 18 of the outer mold, and having a rear end portion 20, formed to be seated on said face, and a forward edge including relatively thick shoulder-forming end portions 21, and a curved thin edged central portion 22, offset from the face 18. The form and arrangement of said portions are such that when the supplemental member bears on the outer mold, as indicated by Figures 1, 5 and 6, and the outer and inner molds exert pressure on the outsole, the supplemental mold compresses and molds the heel end of the outsole, the feather edge 16 being pressed against the shank piece, as shown by Figures 7 and 10. At the same time, the thicker edge portions 21 indent the outer surface of the outsole, and form thereon the transverse shoulder shown by Figure 10, said shoulder being composed of two portions 24 of maximum depth at the opposite edges of the outsole, and disappearing at the longitudinal center thereof. Said shoulder defines the forward end of the heel seat, and is offset therefrom, so that when the recessed end of the wood heel 25 is seated on the heel seat, the shoulder portions 24 overlap and snugly fit upper portions of the breast of the heel, as indicated by Figures 10 and 10^a, a close joint being thus formed at the intersection of the shank portion of the outsole with the upper portion of the breast.

It will be seen that the heel seat and shoulders are formed entirely by the sole-leveling operation, the heel end of the outsole being adapted by the feather edge 16 to be conformed by the supplemental mold member to the recessed end of the heel 25, so that the usual cutting and trimming of the heel end of the outsole by a hand-operated knife, to enable it to conform to the recessed end of the heel is obviated. Such trimming is objectionable, because of the time and labor, and the liability of error involved thereby. The supplemental mold member may be maintained in operative relation to the outer mold 17 by any suitable means, the preferred means being as next described.

The ends of the member are provided with upstanding ears 28. Links 29 are connected by pivots 30 with the ears 28, and by pivots 31 with the outer mold 17. The length of the links is such they may be swung on the pivots 31, to carry the supplemental mold member away from the pressing face of the outer mold when the use of the supplemental member is not required. The ears 28 are provided with slots 32, receiving the pivots 30, and permitting adjustment of the supplemental mold member.

Spring detents 33 may be provided to yieldingly hold the supplemental mold in its operative position, said detents being fixed to opposite sides of the outer mold member and adapted to yieldingly engage the links 29.

Another detent 33^a may be provided to yieldingly hold the supplemental mold in its inoperative position, as shown at the left-hand portion of Figure 1. The inner mold member may be provided with a marking die 34, adapted to indent the inner surface of a shank piece supported by said member, and thus mark the shank piece 15, to indicate the size of the shoe. 70

It is obvious that my invention is not limited to the preparation of heel seats for Cuban heels, and may be adapted to prepare seats for full Louis and half Louis heels. 75

I claim:

1. A supplemental mold member formed to compress and mold the heel end of the outsole of a supported shoe, to form thereon a heel seat conforming to the recessed end of a wood heel, and a transverse shoulder defining the forward end of the heel seat and offset therefrom, to overlap the upper portion of the heel breast, said member being provided with means whereby it may be engaged with the outer mold of a sole-leveling machine, and located in its operative position relative to said mold, said member being a plate formed to extend across the heel end of the outer mold face, and having a rear end formed to be seated on said face, and a forward edge including relatively thick shoulder-forming end portions, and a curved thin-edged central portion offset from said face. 80 85 90 95

2. The combination with the outer mold of a sole-leveling machine, of a supplemental mold member formed to bear on and extend across the heel portion of said mold and co-operate therewith in forming, on the heel end of the outsole of a shoe supported by the inner mold of the machine, a heel seat conforming to the recessed end of a wood heel, and a transverse shoulder defining the forward end of the heel seat and offset therefrom, to bear on the upper portion of the heel breast, and means movably connecting said member with the said outer mold. 100 105 110

3. The combination with the outer mold of a sole-leveling machine, of a supplemental mold member formed to bear on and extend across the heel portion of said mold and co-operate therewith in forming, on the heel end of the outsole of a shoe supported by the inner mold of the machine, a heel seat conforming to the recessed end of a wood heel, and a transverse shoulder defining the forward end of the heel seat and offset therefrom, to bear on the upper portion of the heel breast, said member having upstanding ears at its opposite ends, and links pivoted to said ears and to the outer mold, said links permitting the location of the mold member in its operative position relative to the outer mold, and its removal from said position. 115 120 125

In testimony whereof I have affixed my signature.

EDWARD J. GOODWIN.
